United States Patent Office

Des. 191,864
Patented Dec. 5, 1961

191,864

MACARONI

Edward De Lancellotti, Rockville Center, N.Y., assignor to Buitoni Foods Corp., South Hackensack, N.J., a corporation of New York

Filed Nov. 14, 1960, Ser. No. 62,820

Term of patent 14 years

(Cl. D8—1)

FIG. 1.

FIG. 3.

FIG. 2.

FIG. 4.

FIG. 1 is a side elevational view of a macaroni embodying my design;

FIG. 2 is an elevational view looking at the other side of said macaroni;

FIG. 3 is an end elevational view looking from the left to the right in FIG. 1; and

FIG. 4 is a top plan view of said macaroni as oriented in FIG. 1.

I claim:

The ornamental design for a macaroni, substantially as shown.
